Oscar E. Gartin.
Dated.

UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

FEEDING MECHANISM.

Application filed June 2, 1921. Serial No. 474,406.

My invention relates to feeding mechanisms and more particularly to feeding mechanism for rock drills of the type known as stoppers.

- 6 An object of my invention is to provide an improved feeding mechanism. Another object of my invention is to provide an improved feeding mechanism for rock drills. A further object of my invention is to provide an improved feeding mechanism for rock drills of the general type known as stoppers whereby greater length of feed may be obtained and whereby the initial point at which the entire normal feeding capacity of 15 the feeding mechanism brought into effect may be varied. Other objects of my invention will appear in the course of the following specification and the appended claims.
- 20 In the accompanying drawings, I have shown for purposes of illustration, one form which my invention may assume in practice.

In these drawings,—

- 25 Fig. 1 is a plan view of a stoper provided with my improved feeding mechanism.

Fig. 2 is a view in longitudinal central section on the line 2—2 of Fig. 1 and on an enlarged scale.

- 30 Fig. 3 is a transverse section on the line 3—3 of Fig. 2.

For purposes of illustration I have shown my improved extensible feeding mechanism in use with a stoping drill which comprises a pressure fluid operated motor 1 provided 35 with a control valve 2 and adapted to operate upon a drill steel 3.

- 35 The motor 1 is provided with a rod 4 by which it is, in the present instance, connected with my improved feeding mechanism. The rod 4 is made hollow as indicated at 5 and is connected by way of a fluid conducting passage 6 with a valve 2 which controls the feed in a well known manner. Adjustably mounted on the rod 4 is a cylinder 7 provided with a bore 8 in which a piston 9 is disposed, the cylinder being movable relative to the piston under the action of pressure fluid supplied to the cylinder bore 8. The piston 9 comprises a head which is provided with a rearwardly extending piston rod or stem 10 upon which is arranged at its rear extremity a point 11 adapted to engage a wall of the stope, or timbering of any kind, and to serve as a fixed point relative to

which the drill as a whole may move when fed toward the work. The piston rod 10 is made hollow and of a suitable size to telescope over the rod 4 and a series of channels 12 are cut into its inner periphery to permit the free supply of fluid around the exterior of the rod 4 to the front end of the cylinder 7. A cross bar 13 is rigidly secured to the rear end of the piston rod 10 and is connected by means of side rods 14 with a sliding clamp 15 which surrounds the exterior of the cylinder 7 and controls the feed of the cylinder relative to the piston.

For the purpose of controlling the relative position of the cylinder 7 with respect to the rod 4, I provide a clamp mechanism 17 by 70 partially splitting a collar formed integral with the front end of the cylinder 7 and placing within the groove 18 within the collar a band of friction material 19 which is adapted to be compressed about the rod 4 by means comprising a bolt 20 and a handled nut 21. A spring controlled stop 22 is provided to prevent the accidental withdrawal of the rod 4 from the cylinder 7.

From the foregoing description, the mode of operation of my improved feeding mechanism will be readily apparent. When it is desired after drilling to the maximum distance permitted by the travel of the cylinder 7 relative to the piston 9, it will be possible 85 by shutting off the air supply to the cylinder and venting the latter by connecting the supply port 6 with a circumferential groove 6^a and a vent port 7^a respectively formed in the throttle valve and the valve casing to move 90 the cylinder 7 rearward on the piston 9, and by moving the cylinder 7 as a whole backward along the rod 4 and again fixing it relative thereto to continue the feed for a further distance. This mechanism is of particular utility in cases where the changes of steel are not uniform. For example, if a hole of a depth of twenty inches has been drilled and if the travel of the cylinder 7 relative to the piston 9 is twenty inches, if the front of the drill is still six inches from the face of the rock after the cylinder has traveled the full twenty inches, it will be obvious that this steel could not be completely used unless some other means than the piston 9 and cylinder 7 were provided. With my improved construction, however, at 95 the end of the feed which is possible by 100 105

means of cylinder and piston, that is, twenty inch feed in the case assumed, the drill runner merely cuts off his air-supply to the feed cylinder and releasing the clamp 17, forces 5 backward the entire feed cylinder 7 a distance of 6 inches and then reclamps it to the rod 4. The rearward motion of the cylinder 7 has placed the piston 9 six inches forward in the cylinder and the cylinder 7 then has 10 a distance of six inches available for forward feed before the rear end of the cylinder again comes in contact with the piston 9. This will permit the running in of the hole to the full available length of the steel and accord- 15 ingly will not render necessary the sacrific- 20 ing of a portion of the possible drilling that could be accomplished with any given steel. This is but one example of the way in which this mechanism might prove useful and other 25 ways will readily suggest themselves to one skilled in the art. It will also be evident that if the drilling is not too hard the mere release of the clamp 17 will extend the feed by reason of the air acting on an area equal 30 to the area of a circle having the same diameter as the rod 4 and forcing the motor 1 and rod 4 forward.

While I have in this application specifically described one form which my invention 35 may assume in practice, it will be understood that this form of the same is shown for purposes of illustration and that the invention may be modified and embodied in other forms without departing from its spirit or 40 the scope of the appended claims.

What I claim as new and desire to secure by Letters Patent is:

1. In a drilling apparatus, a drilling tool, 45 and feeding means therefor comprising an extension member secured to and movable with said tool, a normally stationary cylindrical hollow member, a member disposed about said cylindrical hollow member and connectible in various positions to said first mentioned member, and means for effecting relative movement between said cylindrical hollow member and said third mentioned member.

2. In a drilling apparatus, a drilling tool, 50 and feeding means therefor comprising a member secured to and movable with said tool, a normally stationary cylindrical hollow member, a member disposed about said cylindrical hollow member and connectible 55 to said first mentioned member, said last mentioned member being movable relative to said first mentioned member and said hollow member, means for effecting relative movement between said hollow member and said third mentioned member, and means operable to retard the movement of said first mentioned member relative to said third mentioned member.

3. In a drilling apparatus, a drilling tool, 60 and feeding means therefor comprising a

member secured to and movable with said tool, a normally stationary cylindrical hollow member relative to which said first mentioned member is movable, a member disposed about said cylindrical hollow member 70 and connectible to said first mentioned member, said last mentioned member being movable relative to said hollow member, means for effecting relative movement between said members, and manually controllable means 75 to permit said movements to occur simultaneously or separately.

4. In a drilling apparatus, a drilling tool, 80 and feeding means therefor comprising an extension rod secured to and movable with said tool, a feed cylinder adjustable longitudinally of said rod and connectible thereto, a normally stationary feed piston contained in said cylinder, and means for sup- 85 pllying fluid to said cylinder to effect move- 90 ment of the latter relative to said piston.

5. In a drilling apparatus, a drilling tool, 95 and feeding means therefor comprising an extension rod secured to and movable with said tool, a cylinder operatively connected to said rod, a normally stationary feeding piston contained in said cylinder and tele- 100 scopically arranged with respect to said rod, and means for supplying fluid to said cyl- 105 95 inder to effect movement of the latter rela- tive to said piston.

6. In a drilling apparatus, a drilling tool, 100 and feeding means therefor comprising an extension rod secured to and movable with said tool, a cylinder member, a normally sta- 105 tionary piston member contained in said cyl- 110 105 inder and having a piston rod secured thereto, said cylinder and piston being telescopic- 110 ally arranged with respect to said first men- tioned rod, means for securing one of said members in a plurality of different adjusted positions with respect to said rod, and means for supplying pressure fluid to said cylinder member to effect movement of the latter relative to said piston member.

7. In a drilling apparatus, a drilling tool, 115 and feeding means therefor comprising an extension member secured to and movable with said tool, a feed cylinder, means for connecting said cylinder in a plurality of different longitudinally adjusted positions with respect to said member, a normally stationary piston contained in said cylinder and provided with an abutment engaging element, and means for supplying pressure fluid to said cylinder member to effect move- 120 ment of the latter relative to said piston.

8. In a drilling apparatus, a drilling tool, 125 and feeding means therefor comprising an extension rod secured to and movable with said tool, a cylinder, means for securing said cylinder to said rod in a plurality of longitudinally adjusted positions, a nor- 130 mally stationary piston contained in said cylinder and provided with an abutment

engaging element, and means for supplying pressure fluid to said cylinder to effect movement of the latter relative to said piston.

9. In a drilling apparatus, a drilling tool, and feeding means therefor comprising an extension rod secured to and movable with said tool, a cylinder within which said rod extends, the position of said cylinder being adjustable relative to said rod, a normally stationary piston contained in said cylinder adapted to telescope with said rod and provided with an abutment engaging element, and means for supplying pressure fluid to said cylinder to effect movement of the latter relative to said piston.

10. In a drilling apparatus, a drilling tool, and feeding means therefor comprising an extension rod secured to and movable with said tool, a cylinder within which said rod extends, the position of said cylinder being adjustable relative to said rod, a normally stationary piston contained in said cylinder adapted to telescope with said rod and provided with an abutment engaging element, means between the exterior of said rod and said piston for connecting the interior of the latter with the cylinder at a point in front of the piston, and means for supplying pressure fluid to said cylinder to effect movement of the latter relative to said piston.

11. In a drilling apparatus, a drilling tool, and feeding means therefor comprising a hollow extension rod secured to and movable with said tool, a cylinder within which said rod extends, the position of said cylinder being adjustable relative to said rod, a normally stationary piston contained in said cylinder adapted to telescope with said rod and provided with an abutment engaging element, means between the exterior of said member and said piston for connecting the interior of the latter to said cylinder at a point in front of said piston, means for supplying pressure fluid through said hollow rod to said cylinder to effect movement of the latter relative to said piston, and controlling means for said fluid supply.

12. In a drilling apparatus, a drilling tool, and feeding means therefor comprising an extension rod secured to and movable with said tool, a cylinder adjustably arranged with respect to said rod, means for clamping said cylinder to said rod, a normally stationary piston contained in said cylinder and relative to which the latter is movable, and means for supplying pressure fluid to said cylinder to effect movement of the latter relative to said piston.

13. In a drilling apparatus, a drilling tool, and feeding means therefor comprising an extension member secured to and movable with said tool, a member manually adjustable longitudinally of said member and connectible thereto, a normally stationary mem-

ber extending within said adjustable member and relative to which the latter is movable, and means for effecting movement of said adjustable member relative to said stationary member.

14. In a drilling apparatus, a drilling tool, and feeding means therefor comprising a hollow extension rod carried by and movable with said tool, a cylinder manually adjustable longitudinally of said rod and connectible thereto, a normally stationary piston contained in said cylinder, and means for supplying pressure fluid to said cylinder to effect movement of the latter relative to said piston.

15. In a drilling apparatus, a drilling tool, and feeding means therefor comprising an extension member in the form of a hollow rod carried by and movable with said tool, a feed cylinder cooperating with said rod, a normally stationary feed piston contained in said cylinder and relative to which said cylinder is movable, means to permit adjustment of both said cylinder and piston relative to said hollow rod, and means for supplying pressure fluid to said cylinder to effect movement of the latter relative to said piston.

16. In a drilling apparatus, a drilling tool, an extension member secured to and movable with said tool, a cylinder cooperating with said member and movable longitudinally relative thereto, a normally stationary piston contained in said cylinder and relative to which said cylinder and said member are movable, means for supplying pressure fluid to said cylinder to effect movement of the latter and said member relative to said piston, and means permitting independent or simultaneous movement of said cylinder and member.

17. In a drilling apparatus, a drilling tool, and feeding means therefor comprising an extension member secured to and movable with said tool, a feed cylinder connectible to said member in different longitudinally adjusted positions, a normally stationary feed piston contained in said cylinder, and means for supplying pressure fluid to said cylinder to effect relative movement between the latter and said piston.

18. In a drilling apparatus, a drilling tool, and feeding means therefor comprising an extension rod secured to and movable with said tool, a feed cylinder within which said rod extends, means for securing said cylinder to said rod in different longitudinally adjusted positions, a normally stationary feed piston contained in said cylinder and having an abutment engaging piston rod secured thereto, and means for supplying pressure fluid to said cylinder to effect movement of the latter relative to said piston.

19. In a drilling apparatus, a drilling tool,

4 and feeding means therefor comprising an extension rod secured to and movable with said tool, a feed cylinder within which said rod extends, means for securing said cylinder to said rod in different longitudinally adjusted positions, a normally stationary feed piston contained in said cylinder and having an abutment engaging piston rod secured thereto, means for supplying pressure fluid to said cylinder to effect movement of the latter relative to said piston, and means for controlling the movement of said cylinder.

10 20. In a drilling apparatus, a drilling tool, and feeding means therefor comprising a

normally stationary member, a plurality of relatively movable elements cooperating therewith and each having means whereby it may be moved by fluid pressure, one of said relatively movable elements being secured to said tool, means for effecting movement of said elements relative to said stationary member, and means permitting simultaneous movement of said elements or of either independently of the other relative to said stationary member by fluid pressure.

25 In testimony whereof I affix my signature.

ELMER G. GARTIN.
